FRANK PARDEE, JR., OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA

BAG LOADING CHUTE

Application filed December 17, 1930. Serial No. 502,896.

This invention relates to an apparatus for lowering material such as coal or the like and aims to provide a device adapted to facilitate filling bags or other receptacles with coal or similar material handled by a chute. While not limited thereto the invention is well suited for uses in connection with various types of extensible lowering chutes disclosed in my co-pending application, Serial No. 10 456,365, filed May 18, 1930.

The various features of the present invention will be fully apparent from the following specification when read in connection with the accompanying drawing and the features of novelty will be defined with particularity in the appended claims.

Referring in detail to the drawing—

Fig. 1 is an elevation showing a coal storage bin having an extensible discharge chute associated therewith and equipped with a bag-loading device embodying the present invention.

Fig. 2 is an enlarged detailed view, the lowering chute being shown in vertical section, the bag filling device being shown, in the position it assumes after a quantity of material has been discharged to the bag;

Fig. 3 is an elevation from the right side of Fig. 2;

Fig. 4 is a vertical section illustrating a modification of the invention; Fig. 5 illustrates a further modification; Fig. 6 is a section on line 6—6 of Fig. 5.

Referring in detail to the drawing, 10 represents a bin used for storage of coal or similar material. Mounted on the bin there is a guide track 12 formed of channel shaped members so as to provide a run-way to receive rollers 14 carried by a plurality of hingedly connected sections 16 of the chute. Each section 16 includes a plurality of inclined runway portions 18 and 20 over which the material discharged from the outlet chute 22 of the bin 10 is adapted to travel. The flow of material from the bin 10 is controlled by a vertical movable gate 24 operated by a lever or other suitable means not shown.

At its upper extremity, the flexible chute is connected to a cable 26 which in turn is secured to a drum 28 adapted to be rotated

either manually or by power so as to elevate or lower the flexible chute.

At its lower extremity, the flexible chute is provided with a receptacle filling device 30 which is pivotally supported on the studs 32 secured to the lowermost chute section. Springs 34 are connected respectively to spring anchorages 36 and 38 carried by the loading device 30 and the lowermost section of the flexible chute. The springs tend to position the member 30 so that the flow of material from the end of the chute will be prevented. The member 30 is provided with supporting means 40 which may take the form of hooks as shown in Fig. 3. These are adapted to be engaged by the handles 42 of the coal bag 44 or a suitable receptacle. Instead of providing hooks as shown in Fig. 4, the handles of the coal bag may be engaged with cross-bars 48 secured to the member 30 as shown in the modification of Fig. 4. In this modification we have also shown the bag loading device pivotally secured at 50 to the lower end of a lowering chute comprising a plurality of fixed inclined plates 52 and 54 supported by suitable vertical chute structure 56.

The member 30 serves the double function of controlling the flow of material from the chute and also that of supporting the bag or other receptacle and guiding the material into the bag. When the member 30 is in full line position as in Fig. 1, it has a tendency to cause the material in the chute to choke up and the inclination of the run-way portions 18 and 30 is such that when the member 30 is in a substantially horizontal position held by the springs 34, there will be no flow of material from the lowering chute.

The springs 34 may be omitted if desired because the holding capacity of the part of the member 30 on one side of the pivot is greater than that on the other side. Thus, when the member is in the dotted position of Fig. 2, it will tend to stay in such position due to the unbalanced condition of the load held therein. Then, when the member is moved to the inclined full line position of Fig. 2, the flowing material will overbalance

the right side of the member and keep it in the full line position.

When it is desired to fill the bags or other receptacles with coal or the like, the bag handles are engaged with the supports 40-40 and the member 30 is swung about its pivot 32. This permits the coal in the upper sections of the chute to flow downwardly and into the bag. In this manner of operation, one can readily fill a number of coal bags without any appreciable amount of spillage. As soon as one bag is filled the operator lifts it slightly and releases it from the pins 40 whereupon the springs 24 cut off the flow of coal. Then the second bag is engaged and filled and so on until the required shipment has been made up.

The arrangement described is a marked improvement over devices heretofore used. According to prior practice it has usually been necessary to build a platform and to provide a special chute to allow the coal to be bagged in a truck. With such an arrangement, the chute cannot be used for any other purpose.

With the improved device described, the lowering chute can be used both for loading the material in bags, and also for discharging coal or the like material directly into the coal truck with a minimum of breakage. When delivering material directly to the truck the springs 34 may be disengaged and the chute as a whole may be lowered by rotating the drum 28 in the proper direction.

Figs. 5 and 6 illustrate a modification in which the final discharge member 30^a is pivoted at 50^b to the lowermost section 16^a of the flexible chute as shown. The member 30^a instead of being held in substantially horizontal position by a spring such as shown in Fig. 4 is adapted to rest on a projection 58. When the chute fills up with coal the weight will be sufficient to slightly spring the member 30^a so that it can pass the projection 58. In swinging about its pivot it will also pass another projection 60 and will come to rest against a limiting stop 62 bent inwardly from the side wall of the lower member 16^a. The lower projection 60 acts as a sort of a brake, absorbing some of the force before the member finally comes to rest against the stop 62. The side wall of the member 16^a is also provided with an upper stop 64 limiting the movement of the chute in the upward direction. In this modification the bag or other receptacle to be filled is adapted to be hung on outwardly projecting pins 66 secured to side walls of the lower member 16^a as clearly shown.

While in the foregoing I have referred specifically to the utility of the invention in connection with the handling of coal, it is, of course, to be understood that various other materials may be handled equally as well. The material may be discharged in smaller amounts into any suitable smaller receptacle

and the word "receptacle", as used in the claims, is intended to include various articles, such as bags, baskets, pails and like containers.

Various modifications may be made by those skilled in the art without departing from the invention as defined in the appended claims.

What I claim is:—

1. A chute for lowering coal and similar materials having a movable member pivoted centrally of its length so as to be supported in a substantially balanced position on the lower end of the chute, such member being adapted to control the discharge of material from the lower end of the chute, and receptacle supporting means carried by said member.

2. A chute for lowering coal and similar materials having a member pivoted about midway between its ends to the discharge end thereof, adapted to control the flow of material from the chute, yielding means normally tending to hold said member in position to prevent flow of material from the chute and receptacle supporting means secured to said pivoted member at such location that the weight of material discharged into a receptacle carried by said supporting means will tend to hold said member in position to permit flow of material from the chute.

3. A chute for lowering coal and similar materials having a substantially balanced member pivoted intermediate its ends to the discharge end thereof, adapted to control the flow of material from the chute, means acting on one side of the pivot normally tending to hold said member in position to prevent flow of material from the chute, supports on the other side of the pivot projecting from said member and a receptacle detachably engaging said supports and tending to hold said member in position to permit flow of material from the chute.

4. A lowering chute for lowering coal and similar materials having a substantially balanced pivoted member adapted to control the discharge of material from the chute, springs normally tending to prevent flow of material from the chute, and receptacle supports located on said member in offset relationship to its point of pivotal connection with the chute so that the weight of material accumulated in a receptacle supported thereby tends to counteract the action of said springs.

5. A chute for lowering coal and similar material comprising a plurality of sections, each carrying a pair of oppositely inclined runway portions over which the material flows successively, said sections being pivotally hinged to one another at points located substantially along a vertical line extending midway between said runway portions, and a substantially balanced member pivotally secured to the lowermost section of the chute.

and adapted to control the discharge of material therefrom.

6. A chute for lowering coal and similar material comprising a plurality of flexible assembled runway sections pivotally secured to one another and a member pivotally secured intermediate its ends substantially at the center of the lowermost section and adapted to control the discharge of material from the lower end of the chute and stops carried by said lowermost section limiting the angular movement of the pivotally mounted member.

In witness whereof, I have hereunto signed
15 my name.
